CLAIM

The ornamental design for a combination burner unit with side panels and grill plate, substantially as shown and described.

DESCRIPTION

FIG. 1 is a left, front and top perspective view of a combination burner unit with side panels and grill plate showing my new design with the stove being in an open position;

FIG. 2 is a right, rear and bottom perspective view thereof;

FIG. 3 is a left, front and top perspective view thereof showing the grill plate in an alternate position; and The lid, legs, and gas hose in FIGS. 1-3 are shown in broken lines for illustrative purposes only and form no part of the claimed design.

FIG. 1

FIG. 2

FIG. 3
